UNITED STATES PATENT OFFICE.

FREDERICK S. GALLAGHER, OF YONKERS, NEW YORK, ASSIGNOR TO CAMEL COMPANY,
OF CHICAGO, ILLINOIS, A CORPORATION OF MAINE.

DOOR-SECURING DEVICE.

1,168,878.

Specification of Letters Patent. Patented Jan. 18, 1916.

Application filed March 23, 1915. Serial No. 16,817.

To all whom it may concern:

Be it known that I, FREDERICK S. GALLAGHER, a citizen of the United States, residing at Yonkers, in the county of Westchester 5 and State of New York, have invented certain new and useful Improvements in Door-Securing Devices, of which the following is a specification.

My invention relates to devices for securing and sealing the door of a freight car or the like in closed position, and particularly to a construction whereby the sliding side door of a freight car may be secured and sealed after the car has been loaded. In 10 such constructions a hasp on the sliding door is commonly caused to move over a staple secured to a post or stationary frame member of the car, a sliding bolt or pin being then inserted through the staple above the 15 hasp, the movable parts connected together by a wire, and the ends of the wire sealed together. In such devices difficulty is often experienced because of the breaking of the 20 staple and other parts and the loss of some 25 of the same, or removal thereof by unauthorized persons.

The object of my invention is to provide improvements of devices of the character referred to, intended to overcome such difficulties and to provide an efficient construction, which is economical in manufacture, and which cannot readily be tampered with. By my construction a casting or other metal 30 frame member is secured to a post of the car frame. A separate staple is carried by this casting and is removable therefrom for replacement when broken. The staple and casting are so formed, however, as to prevent the removal of the staple without first 35 removing the casting from the car, in one form of my construction, or without gaining access to the interior of the car, in another form of my construction. A hasp carried by the car door encircles this staple when 40 the parts are in operative position, a sliding bolt being dropped through a hole in the outer end of the staple, after the hasp has been positioned, to prevent the removal of the hasp. The bolt slides in a guide formed 45 on the casting and is provided with a lug between the staple and the guide, which lug cannot pass through the guide, so that the bolt cannot be removed without first removing the casting, in the one form of my construction, or without removing the staple 50

from the interior of the car, in the other form referred to, of my construction. The hasp is preferably provided with a lug in line with the lug referred to on the bolt, and these lugs, as well as the portion of the 55 staple in vertical alinement therewith, are provided with alined holes through which a sealing wire may be passed. The bolt also preferably is provided with a pair of openings therethrough which are above and below the staple, when the parts are in their operative positions. A sealing wire may be passed through these openings and around the staple if desired. My invention provides 60 means by which the parts may be secured 65 together in a variety of ways, so that even if the staple is broken at the hole for the sealing wire, or if the lug referred to on the locking bolt is broken, or if the lug referred 70 to on the hasp is broken, openings will still 75 be provided through which a sealing wire may be passed to seal the door in its closed position.

In order that a clearer understanding of my invention may be had, attention is hereby directed to the accompanying drawings forming part of this application and illustrating certain embodiments of my invention.

In the drawings, Figure 1 represents a 80 front elevation of a car door secured, in closed position, to a post of the car frame, Fig. 2 is a horizontal section taken on line 2—2 of Fig. 1, Fig. 3 is an enlarged sectional detail corresponding to the left hand end of Fig. 2, Fig. 4 is an enlarged front elevation of the securing devices shown in Fig. 2, Fig. 5 is partly an elevation at right angles to the view shown in Fig. 4 and partly in section on line 5—5 of Fig. 4, and Fig. 6 is a partial sectional view corresponding 85 to Fig. 5, illustrating a modification of 90 my invention.

Referring to the drawings, I have illustrated at 1 the sliding side door of a freight 100 car supported in the usual manner by rollers 2 on a track 3 secured to the upper ends of the posts 4, 4' of the side frame of the car. Preferably a Z-bar 5 is secured to the front 105 of post 4, this bar having a flange 6 parallel to the face of post 4 with an outwardly curved end 6', the door 1 being received behind flange 6 when it is moved into its closed position. Door 1 has a hasp 7 secured thereto and hinged as shown at 8, this hasp having 110

an opening 7' in the forward end thereof through which the staple is adapted to pass.

A casting or other suitable metallic frame member 9 is secured to post 1 preferably by 5 bolts passing through the flanges 10, 10 of the casting, which bolts may be secured by nuts on the inner side of the car. The casting 9 has a horizontal opening 11 therethrough in which the staple 12 is mounted. 10 This staple, in the form of my invention illustrated in Figs. 4 and 5, is given a T-shape, the T-flange 13 at the inner end of the staple being mounted within a recess 14 formed in the inner face of the casting 9. 15 The casting is provided with a lug 15 on its forward face, provided with a vertical opening therethrough which acts as a guide for the bolt 16, the bolt and guide preferably being given a rectangular or other angular 20 section, to prevent turning of the bolt. The outer portion of staple 12 is provided with a vertical passage therethrough, through which the lower portion of the bolt is adapted to slide, it being understood that when 25 the door is closed, the hasp 7 is positioned over staple 12, on to its seat on casting 9 as shown, after which the bolt is dropped through the hole in the staple referred to, into the position shown in Fig. 5, to prevent 30 removal of the hasp.

The bolt 16 is provided with an outwardly extending lug 17 on its forward face, adapted to rest, when the bolt has been operatively positioned, on the outer top surface 35 of staple 12. This lug cannot pass through the opening in guide-lug 15, and it is therefore obvious that bolt 16 cannot be removed from its housing without first removing staple 12 from its position. The latter cannot be removed, in the form of my device 40 described, without first unbolting the casting 9 from the car frame, because of the engagement of head 13 of the staple in recess 14 between the car frame and the body of the 45 casting 9. In assembling the device, it is necessary to insert the bolt 16 in its guide 15, and then to insert staple 12 in its opening 11 in casting 9, from the inner end, before the casting is bolted to the door post.

50 Hasp 7 is preferably provided with a lug 18 having an opening therethrough, through which bolt 16 extends when in its locking position, in line with the opening through which the bolt passes in staple 12. Thus 55 the hasp 7 is provided with a portion extending in front of the locking bolt, which portion may be above the staple, or as is illustrated, below the staple. The alined outer portions of lug 17 on bolt 16, the 60 staple, and the forward portion 18 of the hasp, have alined vertical openings 19, 20 and 21 extending therethrough, through which a securing device may be passed when the bolt is in its locking position. I have 65 illustrated a wire 22 as extended through

these alined openings, the ends of the wire being sealed together at 23. The bolt is also preferably provided with openings 24 and 25 therethrough, which openings are positioned respectively above the staple and below the lower portion of the hasp when the bolt is in its locking position. A sealing wire may be extended through openings 24 and 25 around staple 12, either as an additional security, or as a substitute for the 75 sealing wire through alined openings 19, 20 and 21. It is obvious that with the construction described, the bolt may be secured and sealed in its locking position in a number of ways. Thus, if the lug 17 on bolt 16 is 80 broken, the sealing wire may be passed through hole 20 in the end of the staple, hole 21 in the hasp and opening 25 in the bolt, or if the lug 18 on the hasp is broken or is not used, the sealing wire may pass through hole 20 in the staple and opening 19 in lug 17, if the latter is intact, or through opening 24 in 85 the bolt if lug 27 is broken. If the staple is broken at hole 20 therethrough, the sealing wire may pass through openings 19 and 21, or 24 and 21, in the bolt and hasp respectively. It will be obvious that a number of 90 such combinations can be made.

In Fig. 6 I have shown a modification of my invention in which staple 12 is provided with a shank 12' of reduced diameter, extending through post 4 of the car and secured on the inner side of the car frame by a nut 12² mounted on the threaded end of shank 12', the T-head 13 of the form of staple first described being omitted. In this form of my device, the staple is readily removed, if the same becomes broken and it is desired to replace it, without removing the casting 9. In this case, the staple is removed outwardly through its opening in the casting, by any one having access to the 105 interior of the car, upon removing nut 12².

It should be understood that my invention is not limited strictly to the exact details of construction described, but that the same includes reasonable equivalents for the 110 constructional features illustrated.

Having now particularly described my invention, what I claim and desire to protect by Letters Patent is as follows:—

1. In door securing devices, the combination of a fixed frame member, a staple secured thereto, having a hole through the outer portion thereof, a hasp, adapted to encircle said staple, and a bolt slidable into position to extend through said hole in the 120 staple, said bolt having a lug on the outer side thereof, above said staple and adapted to seat thereon, and said hasp having a lug thereon, in alinement with said bolt lug, immediately below said staple, and at the 125 130

front side of said bolt, both of said lugs and said staple having alined openings therethrough, through which securing means may be passed, the said opening in the staple 5 being at the outer side of the hole therethrough, through which said bolt extends, substantially as set forth.

2. In door securing devices, the combination of a fixed frame member, a staple secured thereto, having a hole through the outer portion thereof, a hasp carried by a door adapted to encircle said staple, and a bolt slideable into position to extend through said hole in the staple, said bolt having a 10 lug on the outer side thereof, and said hasp having a lug in alinement with said bolt lug, said lugs having alined openings therethrough, when the parts are operatively positioned, through which securing means may 15 be passed, substantially as set forth.

3. In door securing devices, the combination of a fixed frame member, a staple secured thereto, having a hole through the outer portion thereof, a hasp carried by a door, adapted to encircle said staple, and a bolt vertically slideable into position to extend through said hole in the staple, said hasp having a lug thereon at the front side 20 of said bolt, immediately below and in alinement with the front end of said staple, so that said bolt, when operatively positioned, extends between the main portion of said hasp and said lug, said lug and the front end 25 of said staple having alined openings therethrough, through which securing means may 30 be passed, substantially as set forth.

be passed, said bolt also having an opening therethrough, through which the securing means may additionally be passed, substantially as set forth.

4. In door securing devices, the combination of a fixed frame member, a staple secured thereto, having a hole through the outer portion thereof, a hasp carried by a door, adapted to encircle said staple, and a bolt slideable into position to extend through 40 said hole in the staple, said bolt having a lug on the outer side thereof, and said hasp having a lug in alinement with said bolt lug, said lugs having alined openings therethrough, and said bolt having openings 45 therethrough, above and below said staple, when the parts are operatively positioned, substantially as set forth.

5. In door securing devices, the combination of a frame member, a casting removably secured thereto, a staple extending outwardly through an opening in the casting having a hole in the outer portion thereof, said staple having a flange on its inner end seated in a recess in the inner face of the 50 casting, a movable member, a hasp thereon adapted to encircle the staple, and a locking member adapted to extend through the hole in said staple, substantially as set forth.

This specification signed and witnessed 55 this 19th day of March, 1915.

FREDERICK S. GALLAGHER.
